UNITED STATES PATENT OFFICE.

RICHARD VAN DOHLAN, OF LEAVENWORTH, KANSAS, ASSIGNOR OF ONE-FOURTH TO
FREDERICK C. JOHNS, OF EAST ST. LOUIS, ILLINOIS.

PROTECTING DEVICE.

1,355,719.

Specification of Letters Patent. Patented Oct. 12, 1920.

Application filed March 20, 1919. Serial No. 283,945.

To all whom it may concern:

Be it known that I, RICHARD VAN DOHLAN, a citizen of the United States, residing at Leavenworth, in the county of Leavenworth and State of Kansas, have invented certain new and useful Improvements in Protecting Devices; and I do hereby declare the following to be a full, clear, and exact description of the invention, such as will enable others skilled in the art to which it appertains to make and use the same.

This invention relates to protecting devices, and more particularly to a device specially adapted for use in connection with internal combustion engines.

The primary object of the invention is to provide a device of the character stated of simple construction and operation which may be readily connected into the fuel supply pipe for the carburetor of an internal combustion engine, this device serving to thoroughly strain the fuel so as to remove particles of foreign materials therefrom before the fuel flows into the carburetor, thus preventing stoppage or clogging of the carburetor from this cause.

A further object is to provide a straining device of the character stated of simple construction which may be readily disassembled for cleaning and removal of foreign materials therefrom.

Further objects will appear from the detailed description.

In the drawings:

Fig. 1 is a side view of a carburetor protector constructed in accordance with my invention as applied.

Fig. 2 is a central vertical section through the protector.

Fig. 3 is a detail section through the feed pipe for supplying fuel from the protector to the carburetor showing the supplemental strainer interposed therein.

Fig. 4 is a transverse section taken along the line 4—4 of Fig. 1.

A cylindrical casing 1 of brass or other suitable material is provided, adjacent its lower end, with a nipple 2 and, a short distance from its upper end, with a nipple 3 which is disposed diametrically opposite to nipple 2. The bottom 4 of this casing is rounded, as shown, to provide a water well, and is provided with a central drain cock 5

for draining and cleaning of the same. The upper end portion of casing 1 is exteriorly threaded to receive a rounded cover 6 provided with a depending interiorly threaded flange 7 for securing the same in position, this cover being provided in its under face with an annular recess which receives a packing ring or gasket 8 of felt, rubber, or other suitable material which fits tightly against the upper end of the casing to form a fluid-tight closure therewith. Nipple 2 is connected by a union joint 9 to a feed pipe 10 for conducting fuel to the carburetor to which this pipe is connected. The nipple 3 is connected to a fuel supply pipe 11 leading from the fuel tank, a coupling 12 and this pipe being connected at its outer end with a supplemental supply pipe 13 which leads direct from the fuel supply tank, this supplemental supply pipe communicating with an auxiliary fuel supply pipe 14 connected to an elbow 15 screwed into the cover 6 and in direct communication with the interior of casing 1 at the top thereof. The supplemental supply pipe 13 is provided, beyond the point of connection of the same with the auxiliary supply pipe 14, with a suitable control valve 16, the auxiliary pipe 14 being provided with a similar valve 17. By means of these valves, the fuel flowing from the supply tank may be admitted to the casing 1 through the top thereof by means of elbow 15, or through nipple 3, as desired.

The supply pipe 13 is provided with a conical strainer 18 of foraminous construction, this strainer being formed either of wire fabric or of finely perforated sheet metal, as desired, and having its apex directed in the direction of flow of the fuel to the casing. A similar strainer 19 is interposed in the pipe 10, this strainer being provided at its broader or base end with an annular flange 20 by means of which it may be secured in position by the union 9 simultaneously with coupling of pipe 10 and nipple 2, strainer 18 being secured in position in a similar manner. The strainer 18 serves to remove the larger particles of foreign materials from the fuel during its flow through pipe 13 and may be removed therefrom by disconnecting the union 13 so as to be readily cleaned and replaced, strainer 19

serving a similar purpose to remove particles of material which may be contained in the fuel after it leaves the cleaning and straining means contained in casing 1, to be 5 later described.

A cylindrical tube 21 is mounted at the center of casing 1 and extends the full length thereof, the ends of this tube fitting snugly against the bottom of the casing and 10 against cover 6 when this cover is in position. The tube 21 is formed of wire fabric of extremely fine mesh, and serves as a supporting column for a plurality of pairs of straining disks, the pairs of disks 15 being designated respectively by the numerals 22, 23; 24, 25; 26, and 27 secured thereto in spaced relation. As will be noted more clearly from Fig. 2, these disks are formed of wire fabric of different meshes, each of the 20 disks having its peripheral portion turned upwardly at right angles to provide a vertical annular flange 28. In practice, disks 22 and 23 are of one-sixty-fourth inch mesh, disks 24 and 25 are one-one hundred and twenty-eighth of an inch, and disks 26 and 27 25 of the finest mesh practical which will permit proper flow of fuel therethrough. Disks 22 and 23 which are of 1/64th inch mesh serve as strainers for separating the larger 30 particles of foreign materials from the fuel, the remaining disks 26 and 27 serve as straining mediums for removing the fine particles of foreign materials from the fuel. In this manner, the disks coöperate to insure 35 thorough and efficient straining of the fuel so as to effectually remove all foreign materials therefrom thus effectually preventing stoppage or clogging of the carbureter due to the presence of minute particles 40 of foreign materials in the fuel, such as occurs where a protector or straining device of this character is not employed. As will be noted, the straining disks are of such diameter as to fit snugly the interior 45 of casing 1, the peripheral flanges 28 of these disks serving to brace the same and to effectually prevent passage of fuel between the disks and the inner face of the casing, the disks and the central tubular support 21 50 upon which they are secured therefore constituting a unit which may be readily removed from the casing, cover 6 being removed, for cleaning, repairs, and other purposes. In the event that any particles of 55 foreign materials should pass through the screen 26, as when the device has been in operation for a considerable period so that the disks are more or less saturated with foreign materials, these particles will be retained by the supplemental screen or strainer 60 19. As previously noted, this strainer, as well as the strainer 18, may be readily removed for cleaning and repairs. In the event that the fuel contains an unusually 65 large amount of foreign materials, it is ad-

mitted to the top of the casing 1 through elbow 15, the larger particles of materials being removed by the top screen 22, after which the fuel is strained and cleaned in the manner described. Under normal conditions, however, the fuel may be admitted 70 through nipple 3 onto the upper surface of disk 23, flowing downwardly through the various disks and the tube 21 so as to be effectually cleaned and strained thereby. 75 If fuel should contain water this will gravitate to the bottom of the casing and collect in the water well from which it may be drawn by means of the drain cock 5.

If desired, though not necessarily, the casing 1 may be provided with a nipple 29 projecting therefrom oppositely to nipple 3. This nipple 29 does not communicate with the interior of the casing and serves to provide a stud to project through a corresponding opening provided through a securing clamp 30 adapted to fit tightly about the casing and provided with an arm 31 which may be secured to the automobile frame for bracing and supporting the casing. Under 80 ordinary conditions, however, the provision of this clamp and the arm 31 thereof will not be necessary since the casing 1 will be connected to the fuel supply and fuel feed pipes so as to be effectually braced and supported thereby. 85

It will be evident that there may be slight changes made in the details of construction and arrangement of the different parts of my invention, and I intend to include all such variations, as fall within the scope of the appended claims, in this application in which a preferred form only of my invention is disclosed. 90

What I claim is: 105

1. The combination with a fuel supply pipe, of a casing, fuel straining means carried thereby, means for optionally admitting fuel to the casing at the top thereof or at a point intermediate the top and bottom of the casing, and a fuel feed pipe communicating with the casing adjacent the bottom thereof for conducting strained fluid therefrom to a carbureter. 110

2. The combination with a fuel supply pipe, of a vertically disposed casing provided with straining means mounted therein, means for admitting fluid to said casing at the top or intermediate the top and bottom thereof, optionally, a feed pipe communicating with the casing adjacent the bottom thereof for conducting strained fuel to a carbureter, and a supplemental strainer removably secured in the supply pipe for straining fluid flowing therethrough. 115

3. In a device of the character described, a casing provided with a removable cover, a tubular supporting member of foraminous construction mounted in the casing and extending axially thereof, a drain cock 120

mounted in the bottom of the casing at the center thereof, a plurality of straining disks secured to said supporting member in superposed spaced relation and fitting snugly the 5 interior of the casing, the supporting member and the disks carried thereby being removable from the casing, and means for admitting fuel to be strained to the casing adjacent the top thereof and for withdraw-

ing this fuel from the casing adjacent the 10 bottom thereof.

In testimony whereof I affix my signature in presence of two witnesses.

RICHARD VAN DOHLAN.
